UNITED STATES PATENT OFFICE.

GUSTAV A. BADER, OF ROCHESTER, NEW YORK.

WORK-CLAMP.

1,278,419.

Specification of Letters Patent. Patented Sept. 10, 1918.

Application filed October 7, 1916. Serial No. 124,277.

To all whom it may concern:

Be it known that I, GUSTAV A. BADER, a citizen of the United States, and resident of Rochester, in the county of Monroe and 5 State of New York, have invented certain new and useful Improvements in Work-Clamps, of which the following is a specification.

The present invention relates to work 10 clamps and more particularly to the type designed for holding small articles which are round or otherwise irregular in cross section, an object of this invention being to provide a reversible movable jaw for holding 15 articles of different diameters, the jaw being so arranged that it is symmetrical with reference to the rest of the clamp and does not project beyond the lines of the remaining portions, whereby the clamp may 20 be readily held in a vise to exert equal pressure upon the fixed and the movable jaw of the clamp.

To this and other ends, the invention consists of certain parts and combinations of 25 parts all of which will be hereinafter described, the novel features being pointed out in the appended claims.

In the drawings:—

Figure 1 is a perspective view of a work 30 clamp constructed in accordance with the present invention;

Fig. 2 is a view partly in longitudinal section through the clamp, the clamp being adjusted for removing a taper pin; and

Fig. 3 is a transverse section on the line 35 3—3, Fig. 1.

Referring more particularly to the drawing, 1 indicates the shank which has lateral extensions 2 and 3 at opposite ends, both 40 projecting in the same direction. The projection 2 serves as the fixed jaw of the clamp while the projection 3 serves as a support for an operating screw 4 which extends through the projection 3 and has a head 5 at one end and a cylindrical portion 6 at the other end. The two extensions are 45 equal in height and are of the same width as the shank 1.

Between the extensions 2 and 3, the shank 50 1 is formed with a guideway preferably provided by grooving the shank 1 at 7 on opposite sides. On this guideway a movable jaw 8 operates, said jaw also having a guideway 55 formed preferably by two parallel ribs or lugs 9. Opposite faces of this jaw 8 are provided with pockets 10 adapted to receive

the cylindrical end of the operating screw 4 so as to hold the movable jaw 8 to the shank while, at the same time, permitting the screw to force the movable jaw 8 toward the fixed jaw 2. This movable jaw has two clamping faces 11 and 12, each of which may be provided with crossed or intersecting grooves 13, the grooves on one side being deeper than the grooves on the other side 60 so as to hold objects of different sizes. The purpose of having the crossing groove in each clamping face is to hold the object either perpendicularly to or parallel with the shank of the clamp. The pockets 10 are 65 arranged at the points of intersection between the grooves so that the pressure is applied in the plane of the object whether it be arranged in one groove or the other. The height of the movable jaw and the width 70 thereof, transversely of the shank, are both substantially coextensive, respectively, with the height and width of each of the two extensions so that, when the clamp as a whole 75 is placed in the vise, equal pressure will be exerted upon the two extensions and the movable jaw, thereby preventing any rocking motion of the work clamp and the vise. Either clamping face of the jaw may be 80 made effective merely by disengaging the movable jaw from the operating screw and turning the jaw 180 degrees, the guideway on the jaw coöperating on the guideway on the shank in both positions.

If desirable, the fixed or stationary jaw 2 90 may have a pocket 14 formed therein for the reception of a pin 15 which will engage one end of a taper pin 16 in order to drive said pin from an object 17, the pocket 10, in this instance, providing a recess in which the 95 pin may enter as it is driven from the object 17.

A work clamp constructed in accordance with this invention provides a simple and inexpensive construction which may be 100 quickly adjusted to present either of two clamping faces on a movable jaw to operative position. Each of these clamping faces is so formed that it may hold objects perpendicularly to or at right angles to the 105 shank of the clamp. The guideways between the movable jaw and the shank are arranged in such a manner that the movable jaw may be made coextensive in width and in height with the stationary jaw, thus permitting the two jaws to be held with equal 110 pressure within a vise,

What I claim as my invention and desire to secure by Letters Patent is:—

1. A work clamp comprising a shank having lateral extensions at opposite ends, one of said extensions serving as a fixed jaw, an operating screw mounted on the other extension, and a reversible movable jaw guided on the shank and having opposite faces formed with pockets for receiving an end 10 of the screw.
2. A work clamp comprising a shank having laterally-turned extensions at opposite ends and guide grooves along opposite sides of the shank between the extensions, the 15 surface of the shank between the grooves being continuous to provide a support for the work and one of said extensions serving as a fixed jaw, an operating member mounted on the other extension, and a reversible 20 movable jaw having depending ribs operating in said guide grooves and having also a width and a length co-extensive, respectively, with the width and the length of each of the two extensions, the ribs being so 25 formed that the jaw may be removed laterally from the guide grooves, and the operating member and an opposite face of the movable jaw having coöperating portions permitting the movable jaw to have either 30 face thereof interlocked with the operating member to hold the jaw to the guides.
3. A work clamp comprising a shank having laterally turned extensions at opposite ends and grooves along opposite sides, one of said extensions serving as a 35 fixed jaw, an operating screw mounted in the other extension, and a reversible jaw having a pair of depending ribs operating

in said grooves for either position of the jaw and also having pockets in opposite faces for receiving an end of the screw to hold the movable jaw to the shank, the ribs being so formed that the jaw may be removed laterally of the grooves.

4. A work clamp comprising a shank having laterally turned extensions at opposite ends and a guideway between the extensions, one of said extensions serving as a fixed jaw, an operating screw mounted on the other extension, and a reversible jaw having a single guideway for coöperating with the guideway on the shank for either position of the jaw, said reversible jaw having pockets in its two clamping faces for receiving an end of the screw to hold the movable jaw to the shank, the jaw being removable laterally of the guideway when the operating screw is disengaged from such jaw.

5. A work clamp comprising a shank having laterally turned extensions at opposite ends and a guideway between the extensions, one of said extensions serving as a fixed jaw and having an opening therein, an operating screw mounted on the other extension, a jaw movable on the guideway and having two intersecting grooves in a clamping face thereof, and also having an opening at the point of such intersection, the jaw being engaged by the operating screw, and a pin engaged within the opening of the fixed jaw and projecting therefrom in line with the opening in the movable jaw.
